10 Claims. (Cl. 84—464)

This invention relates to fountain displays, and more particularly to a control system for varying the amplitudes of the fountain sprays in accordance with the occurrence of particular frequency components of predetermined values in an audio control signal and for varying the intensities of colored illuminating lights for the sprays in accordance with the amplitudes of the particular frequency components.

An object of this invention is to provide a new and improved water fountain display with varying water spray and illumination patterns.

Another object is to provide a water display wherein a plurality of different frequency band pass channels are energized by a controlling sound source to provide varying patterns of water spray amplitudes and illumination therefor.

Still another object is to provide a fountain display system of water sprays and illuminating lights wherein light colors corresponding to various sound frequency bands are varied in intensity as a function of the amplitudes of the particular bands of frequency components in an audio control signal.

A still further object is to provide an electromechanical control system for a fountain display comprising a plurality of liquid spray systems and light-source systems for illuminating the sprays in patterns of color wherein an audio control signal is separated into a plurality of sound-frequency bands, a particular color illuminating system and a particular solenoid valve for controlling the supply of liquid and the amplitude of sprays in a liquid spray system being associated with each such band of sound-frequencies, whereby the amplitudes of the respective bands of sound frequency components control the intensities of the light colors in the associated illuminating systems and the occurrence of the particular frequency components control the operation of the solenoid valves so as to vary the visual effect of the display in accordance with the characteristics of the audio control signal.

Additional objects and advantages of the invention will be readily apparent from the reading of the following description of a device constructed in accordance with the invention, and with reference to the accompanying drawings thereof:

FIGURE 1 is a simplified schematic view of the electro-mechanical control system of a preferred embodiment of the invention;

FIGURE 2 is a plan view of the fountain display showing the arrangement of spray nozzles and colored lights for illuminating the water sprays;

FIGURE 3 is a sectional view taken along the line 3—3 in FIGURE 2; and,

FIGURE 4 is a circuit diagram of the electrical system for controlling the intensities of the various colored lights and the action of the solenoid valves for regulating the rate of flow of water to the various spray nozzles.

Referring to the drawings, an audio input signal from an audio-frequency source, such as a radio, recording, microphone, or the like, is delivered to a preamplifier 10 for raising the voltage level of the input signal. The pre-amplifier output signal is transmitted to a pair of conventional amplifiers 15 and 16. The output of the amplifier 15 may be used to power a loudspeaker or loudspeakers 18 and the output of amplifier 16 is transmitted to a group of frequency selective channels which separate

2

the signal into a plurality of different bands of sound-frequency components.

Each channel includes an amplifier 19, a frequency separation filter network 20, an amplifier 21 for the filtered signal, and a rectifier and voltage doubler 22 wherein the input signal is converted to a direct current voltage whose amplitude varies in accordance with the amplitude of the audio input signal. The direct current voltage is then transmitted to each of a pair of direct current amplifiers 23 and 24, the amplifier 23 controlling the operation of a particular illuminating system 25 and the amplifier 24 controlling the operation of a particular solenoid valve 26.

The output of the amplifier 23 which is representative of the controlling sound in channel I, both in amplitude and in frequency, is transmitted through a power control magnetic amplifier 27 and a switch device 28 which transmits current to the particular lighting system 25 which varies in accordance with the direct current output of amplifier 23. Thus, any change in output current of the amplifier 23 is accompanied by a change in intensity of the light emitted by the particular light system associated therewith. Similarly, the direct current output of the amplifier 24 is delivered through an electromagnetic relay 29 to control the operation of a switch device 30 which varies the supply level of current to the solenoid valve 26. The valve 26 is disposed in a conduit for supplying liquid under pressure from a pump or pressure source 31 to the spray nozzles 32. The operation of the valve as controlled by the channel output current is such that the size of the valve opening is increased to a size corresponding to an all-on condition when the occurrence of a signal in the frequency selective channel operates the relay to increase the current output of the switch device 30.

The spray nozzles are preferably arranged in a pattern to produce a particular visual effect, usually with orifices pointing in a generally upward direction. After being ejected from the spray nozzles, the liquid may be collected in a tank or accumulator 33 where it is picked up and re-pressurized by the pump if a recirculating system is used. A drain 34 may be provided for the accumulator if no recirculating is desired. However, if it is not desired to collect the falling liquid from the sprays, the accumulator may be eliminated and the pump connected to some other liquid supply means.

It is thus apparent that the size of the valve opening or orifice is varied in accordance with the current supplied from the switching device 30 as determined by the occurrence of particular frequency components in the audio control signal to vary the height of the water spray. Similarly, the intensity of the light-color in the illuminating system is varied in accordance with the current supplied from the switching device 28. In this manner, when a number of channels are provided to control a number of spray nozzles and a number of lighting systems, a varying spray and light pattern is produced to provide an overall visual effect which changes in accordance with the frequency and amplitude characteristics of a controlling audio signal.

Referring to FIGURES 2 and 3, a suitable arrangement of water spray and illuminating systems includes a spray nozzle 39, and water spray systems 40 and 41 comprising concentric circular arrangements of spray nozzles 40a and 41a, respectively. Spray systems 42 and 43 comprise linear arrays of spray nozzles 42a and 43a in collinear relationship and extending radially from the center of the circular spray systems on opposite sides thereof. The liquid supply system includes a tank 45 having a return conduit 46 communicating with the tank through an accommodating aperture in the bottom of the

tank. Liquid from the tank is supplied through conduit 46 to the inlet of a liquid pump 47 adapted to operate continuously to supply liquid under pressure to the spray systems. The outlet of the pump communicates with a manifold conduit 48 having a plurality of outlet conduits, 49, 50, 51 and 52 which deliver liquid under pressure to the spray systems 42, 43, 41 and 40, and spray nozzle 39, respectively. A solenoid valve 55, connected in the manifold conduit 48 between the pump outlet and the junctions of the outlet conduits with the manifold conduit, controls the rate of flow of liquid to all of the spray systems simultaneously. A manually operated valve 56 and solenoid valves 57, 58, and 59 connected in the outlet conduits 49 to 52, respectively, also control the rates of flow of liquid to their individual associated spray systems.

The solenoid valves 57, 58 and 59 are controlled by a frequency selective network, schematically illustrated in FIGURE 1, having low frequency, middle frequency, and high frequency band pass channels, respectively. The solenoid valve 55, however, is not frequency selective in that it is connected to a signal channel which does not include a band-pass filter. The valve will operate to allow greater flow of liquid whenever the amplitude of any frequency in the audio input signal is above a predetermined value.

In the embodiment of the invention illustrated in FIGURES 2 and 3, four lighting systems are included. One lighting system includes blue lights 61 and 62 controlled by the output of a low frequency band-pass channel. A system of green lights 63 and 64 is controlled by a middle frequency band-pass channel, a system of red lights 65 and 66 is controlled by a high frequency band-pass channel, and a system of white lights 67 and 68 is controlled by output of the composite channel CC which is also adapted to control the operation of the solenoid valve 55. It is apparent, of course, that any number of lighting systems and water spray systems may be provided in the fountain display, each of which may be adapted to be controlled by a particular frequency selective channel. In addition, the number of such frequency selective channels may be varied as desired.

The solenoid valves are each adjustable in high-flow and low-flow maximum and minimum settings and such variable adjustment is also desirable for the manually operated valve 56.

Referring particularly to the circuit diagram of the electrical control system, the audio input signal or voltage is applied across the input terminals 70 and 71 of a pair of conductors 72 and 73, the conductor 72 being connected to ground. The input signal or voltage is impressed across a coupling capacitor 74, conductor 75, and a variable resistance or potentiometer 76. One terminal of the variable resistance is connected to the conductor 72 by a conductor 77. The slide contact 78 of the variable resistance is connected to one side of each of the respective channels, the other side of each of the channels being connected to ground, so that the potentiometer 76 controls the range of the input voltage applied across the channels and thus the sensitivity of all channels simultaneously.

Channel I, illustrated in detail in FIGURE 4, passes a band of low frequency components of the audio input signal and channels II and III are designed to pass bands of middle and high audio frequencies, respectively. Since the channels are substantially identical, differing only in the band-pass characteristics of each channel, a description of channel I will suffice to describe all of the channels.

The potentiometer contact 78 is connected to the control grid 79 of an amplifier electric discharge device 80 in channel I and to the grids of corresponding amplifier electric discharge devices of the other channels. The cathode 81 of the electric discharge device is connected to ground through a bias resistor 82 and its anode 83 is connected to one side 84 of a direct current supply circuit through a resistance 85, conductors 86 and 87, 70

filter resistor 88 and conductors 89 and 89a. The other side 89b of the direct current supply circuit is connected to ground.

A filter network 90 is connected across the anode-cathode circuit of the amplifier electric discharge device 80 and the bias resistor 82 through the conductor 93, a coupling capacitor 94 and the conductor 95. The filter network includes a resistance 96, one of whose sides is connected to the coupling capacitor 94 through the conductor 95 and a pair of capacitors 97 and 98 having one pair of sides connected to opposite side of resistance 96 and their other sides connected to the conductor 95. The output of the filter network 90 is connected across the control grid 102 and the cathode 103 of an amplifier electric discharge device 104. The conductor 105 connects the grid 102 to the common junction or connection 106 of the capacitor 98 and the resistance 96 of the filter network, and to the conductor 72 through the resistance 107.

It will be apparent to those skilled in the art that as the conductivity of the electric discharge device 80 varies in accordance with the audio input voltage across the input terminals 70 and 71, the filter network 90 will transmit a voltage of preselected frequency components only across the control grid 102 and cathode 103 of the amplifier electric discharge means 104. The electric discharge means 104 also includes an anode 112 connected to the side 84 of the direct current supply circuit through the resistance 113, the conductor 87, conductor 89 the resistance 88 and the conductor 89a. The electric discharge device 104 and the electric discharge device 80 may be in the same envelope and are preferably of the high vacuum type. A rectifier and voltage doubling network 115 is connected across the anode-cathode circuit of the electric discharge device 104 through a conductor 116 connected to the common connection or junction 117 of the resistance 113 and the anode 112 of the electric discharge device, the conductor 72, the conductor 108 and the resistance 109.

The rectifier and voltage doubling network includes a pair of diodes or semi-conductor type rectifiers 122 and 123. The conductor 120 is connected to the common junction or connection 126 of the rectifiers 122 and 123. A capacitor 128 is connected across the rectifiers by the conductors 129, 130, 131 and 72. A variable resistance 133 connected across the capacitor 128 by the conductors 134, 72, 135 and 130, controls the rate of discharge of the capacitor 128. It will be apparent to those skilled in the art that when the filtered and amplified audio input voltage is fed to the input of the rectifier and voltage doubler circuit, the capacitor 128 is charged to twice the peak voltage of audio input voltage as the rectifier 122 and 123 alternately conduct positive and negative half cycles of the input voltage.

The rectified output voltage of the rectifier and voltage doubler circuit is impressed across the control grid 136 and the cathode 137 of an amplifier electric discharge device 138 by means of the conductor 139, a variable resistance or potentiometer 140, and the conductor 141. The slide contact 142 of the variable resistance is connected to the control grid of the electric discharge device 138 so that the potentiometer controls the range of input voltage applied across the grid-cathode circuit and thus the sensitivity of the electric discharge device. The cathode 137 is connected to ground through bias resistors 143 and 144 connected in series to the conductor 72. The electric discharge device includes an anode 145 connected to the positive side 84 of the direct current voltage supply through conductors 146 and 89a. A suppressor grid 154 is connected to the cathode and is disposed between the anode and a screen grid 155 of the device. The screen grid is connected to the side 84 of the direct current supply through a voltage dropping resistor 156, the conductors 86 and 87, filter resistor 88, and conductors 89 and 89a. A pair of capacitors 157 and 158 having sides connected to opposite sides of the

resistor 88 and their other sides connected to ground, constitute with the resistor 88 a resistance-capacitance filter for the direct current voltage supply.

The control winding 160a of a magnetic amplifier 160 is connected across the resistance 144 by means of the conductors 72 and 72a. The magnetic amplifier may be of any suitable type such as the commercially available amplifier manufactured by Magnetics, Inc., Butler, Pa. under the designation Type-4536-001. It will be apparent that the output voltage across the resistor 144 varies in accordance with the conductivity of the electric discharge means 138 which in turn varies in accordance with the voltage applied across the grid and cathode of the electric discharge means 138. The current in the control winding thus varies in accordance with the conductivity of the electric discharge means 138.

The magnetic amplifier 160 is adapted to regulate the action of a switching circuit 165 for controlling the supply of power from a suitable A.C. power supply 170 to a particular illuminating system for the fountain installation. The switching circuit includes a pair of switching means 171 and 172, such as silicon controlled rectifiers, which are connected reversely in parallel relative to one another and in series with the lamps L constituting the load connected across the main conductors 173 and 174 which are connected to the alternating current input terminals 175 and 176. The anode 177 of the rectifier 171 is connected to the main conductor 173 by the conductor 178 while its cathode 179 is connected through conductors 180 and 181 to one side of the load L. The other side of load L is connected to the other main conductor 174. The anode 183 of the rectifier 172 is connected to one side of the load through the conductors 184 and 181, and its cathode 185 is connected to the main conductor 173 by the conductor 186.

It will be apparent that since the rectifiers 171 and 172 are connected reversely in parallel relative to each other and in series with the load L, they will transmit alternate half cycles of the alternating current to the load when they are rendered alternately conductive by appropriate control potentials.

The point in the half cycle during which the rectifier 171 is rendered conductive is controlled by the potential applied across the gate or control member 188 and the cathode 179. The gate is connected to one side of the secondary winding 190a of a transformer 191 having a primary winding 190b and a core 192, through a conductor 193, a semi-conductive device or half wave rectifier 194 and the conductor 195. The cathode 179 is connected to the common junction 196 of the primary and secondary windings through the conductors 180 and 197. The junction 196 is of course connected to the main conductor 174 through the conductors 197 and 180 and the load L. The other side of the primary winding 190b of the transformer is connected to the main conductor 173 through the conductor 209, the winding 199 of the magnetic amplifier 160 and the semi-conductive device or half wave rectifier 201.

During the half cycle of the alternating current input across the main conductors 173 and 174 in which a positive potential is applied to the anode 177 of the rectifier 171, a positive pulse of current will flow through the semi-conductive device 201, the winding 199 of the magnetic amplifier 160 and the primary winding 190b of the transformer inducing a potential in the secondary winding 190a. The magnitude of the potential applied across the gate and cathode of the rectifier 171 during the half cycle in which a positive potential is applied to the anode 177, hereinafter referred to as the positive half cycle, of the rectifier 171 varies not only in accordance with the voltage across the main conductors but also in accordance with the impedance of the winding 199 of the magnetic amplifier 160 which in turn varies in accordance with the current flowing in the control winding 160a. The windings 160a and 199 are so arranged that the impedance of the

winding 199 to the current now being transmitted by the half wave rectifier is higher when the value of the current flowing through the control winding 160a is high and is lower when the value of the current flowing through the winding 160a is low. Since the rectifier becomes conductive at the time or phase of the positive half cycle at which the potential across the gate and cathode attains a predetermined value during such positive half cycle and since this predetermined value is attained at different times or phases of the positive half cycle depending upon the impedance of the winding 199, the amount of current transmitted by the rectifier 171 during a half cycle will vary directly in accordance with the value of the current flowing in the control winding 160a of the magnetic amplifier during such positive half cycle. For example, if the value of the current in the winding 160a is relatively high during a positive half cycle, the impedance of the winding 199 is relatively high so that the potential across the gate and the cathode of the transistor attains the predetermined value at a later time or phase of the positive half cycle and the rectifier is rendered conductive at a later time during the positive half cycle. If the value of the current in the winding 160a is low, the impedance of the winding 199 is low and the potential applied across the gate and cathode of the rectifier attains the predetermined value at an earlier time of the positive half cycle so that the amount of current during such positive half cycle transmitted by the rectifier 171, which is in effect switched on at an earlier time in the positive half cycle, will be greater. Of course, the impedance of the winding 199 may be so high that the predetermined value is never attained and the rectifier will not be rendered conductive during a particular half cycle.

The rectifier 172 is similarly rendered conductive during the negative half cycles of the alternating current impressed across the main conductors 173 and 174 in accordance with the variations in the current in the winding 160a since its gate or control member 206 is connected to one side of the secondary winding 207 of the transformer 191 through a conductor 209, a semi-conductor device or half wave rectifier 210 and a conductor 211. The cathode 185 is connected to the common junction 212 of the secondary winding 207 and the primary winding 213 of the transformer 191 by the conductor 214. One side of the primary winding 213 is connected to the main conductor 173 by the conductors 214 and 186 and its other side is connected to the main conductor 174 by the conductor 215, the winding 216 of the magnetic amplifier, the conductor 217, the semi-conductive device or half wave rectifier 218, the conductor 181 and the load L. It will be apparent that the amount of current transmitted by the rectifier 172 during each negative half cycle of the alternating current impressed across the conductors 173 and 174 will vary in accordance with the value of the current in the control winding 160a of the magnetic amplifier since the voltage induced in the transformer secondary winding 207 by the current in the primary winding 213 varies in accordance with the impedance of the winding 216 of the magnetic amplifier. When the audio input signal having the frequency components which are transmitted by the filter network 90 is applied across the input terminals 70 and 71, the potential applied to the grid 136 becomes more negative, the electric discharge device is rendered less conductive causing less current to flow through the control winding 160a, the impedances of the windings 199 and 216 decrease and the rectifiers 171 and 172 transmit current to the load alternately during alternate half cycles of the alternating current applied across the input terminals 175 and 176. The conductivity of the electric discharge means 138 varies, of course, with the amplitude of such frequency components.

When the audio input signal applied across the input terminals 70 and 71 does not have frequency components which are transmitted by the filter network 90, the potential applied to the grid 136 causes the device to be conductive to a degree which causes the current in the control

winding 160a to be relatively high and, since the impedances of the windings 199 and 216 are thus relatively high, the rectifiers 171 and 172 do not transmit any current to the load L. It will thus be seen that the intensity of the light emitted by the lamps controlled by a particular channel will vary in accordance with the amplitude of the selected frequency component band which is transmitted by its associated filter, the intensity or the amount of light emitted by the lamps increasing as the amplitude of the selected band of frequency components increases and decreasing as this amplitude decreases.

The audio input signal which is received by a particular channel also controls the operation of a solenoid valve which regulates the flow of liquid to a particular one of the water spray systems. For this purpose, the one side of the output of the rectifier and voltage doubler circuit 115 is connected to the control grid 225 of an electric discharge device 226, having a cathode 227, by means of the conductor 130, the variable resistance or potentiometer 228, and the conductors 229 and 72. The slide contact 230 of the variable resistance is connected to the control grid of the electric discharge device 226 so that the potentiometer controls the input voltage applied to the grid and thus the sensitivity of the electric discharge device. The cathode 227 is connected to the other side of the output of the rectifier and voltage doubler circuit 115 through the conductors 72 and 231, and the bias resistor 235. The screen grid 242 interposed between the control grid 225 and the anode 237 of the device is connected to the side 84 of the direct current supply voltage through a voltage dropping resistor 240, conductors 86 and 87, resistor 88, and conductors 89 and 89a.

The electric discharge device 226 further includes a suppressor grid 236 interposed between the anode and screen grid and connected to the cathode 227. The anode 237 is connected to the positive side 84 of the direct current supply voltage through the conductor 250, the winding 251 of an electromagnetic relay 252, and conductors 89 and 89a.

The relay 252 includes fixed contacts 255 and 256 and a movable contact 257. A neon indicator light 260 is connected in series with the fixed relay contact 256 to the positive side 84 of the direct current supply voltage by means of conductors 261 and 262, the voltage dropping resistor 263, and the conductors 265, 89 and 89a. When an audio input signal which does not have the preselected frequency components is applied across the input terminals 70 and 71, the movable contact 257 of the relay is held in engagement with the fixed contact 255 by the current transmitted to the relay winding 251 by the electric discharge device 226 which is now fully conductive.

When an audio input signal having the preselected frequency components of predetermined amplitude is received by channel I, the potential applied across the grid 225 and cathode 226 becomes more negative and thus causes the current transmitted through the anode-cathode circuit of the electric discharge device 227, the conductor 250, and the relay winding to decrease permitting the movable contact 257 to move from engagement with the fixed contact 255 and into engagement with the stationary contact 256, thus energizing the light.

The movable contact 257, when in engagement with the stationary contact 255, connects the control winding 300 of the magnetic amplifier 301 across the resistance 302 of the voltage divider bridge 303 by means of the conductors 304, 305, 306, 72 and 270. The voltage divider bridge comprises the resistances 302 and 309 connected in series across the input circuit 84 and 89b through the conductors 89a, 89, 312, 313, 306 and 72 and ground. It will thus be seen that whenever the movable relay contact 257 engages the stationary contact 255, the control winding 300 is energized with direct current of a value predetermined by the values of the resistances of the voltage divider bridge and the voltage of the input circuit.

The magnetic amplifier 301 is part of a switching circuit for controlling the supply of current to a particular solenoid valve V. The switching circuit 165a is substantially identical in all respects to the switching circuit 165 associated with the magnetic amplifier 160 and components of this switching circuit have been provided with the same reference characters, to which the character "a" has been added, as are used to designate corresponding components of the switching circuit controlled by the magnetic amplifier 160.

The switching circuit 165a includes a pair of silicon controlled rectifiers 171a and 172a which are connected reversely in parallel relative to one another and in series with the winding of the solenoid valve V constituting the load connected across the power supply conductors 173 and 174. The anode 177a of the rectifier 171a is connected to the main conductor 173 by the conductor 178a while its cathode 179a is connected through the conductors 180a and 181a to one side of the load V. The other side of the load V is connected to the power conductor 174. The anode 183a of the rectifier 172a is connected to one side of the load through conductors 184a and 181a, and its cathode 185a is connected to the power conductor 173 by the conductor 186a. Like the rectifiers 171 and 172, the rectifiers 171a and 172a transmit alternate half cycles of the alternating current to the load when they are rendered alternately conductive by appropriate control potentials applied across their respective gates and cathodes.

The gate 188a of the rectifier 171a is connected to one side of the secondary winding of a transformer 191a through a conductor 193a, a half-wave rectifier 194a and the conductor 195a. The cathode 179a is connected to the common junction 196a of the primary and secondary windings through conductors 180a and 197a. The junction 196a is, of course, connected to the main conductor 174 through the conductors 197a, 180a, and the load V. The other side of the transformer primary winding is connected to the main conductor 173 through conductor 206a, winding 199a of magnetic amplifier 301 and the half-wave rectifier 201a. It will thus be seen, that as in the switching circuit 165, the potential across the gate and cathode of the rectifier 171a varies in accordance with the impedance of the winding 199a of the magnetic amplifier 301, which, in turn, is dependent upon the magnitude of current in the magnetic amplifier control winding.

Whereas the rectifier 171a is adapted to be rendered conductive only during positive half cycles of the alternating supply voltage, the rectifier 172a is adapted to be rendered conductive only during the negative half cycles. The gate 206a is connected to one side of the secondary winding 207a of the transformer 191a through a conductor 209a, a half wave rectifier 210a and conductor 211a. The cathode 185a is connected to the common junction 212a of the secondary winding 207a and the transformer primary winding 213a by the conductor 214a. One side of the primary winding 213a is connected to power conductor 173 by conductors 214a and 186a and its other side is connected to the power conductor 174 by conductor 215a, winding 216a of the magnetic amplifier, conductor 271a, half-wave rectifier 218a, conductor 181a and the load V.

The admission of the channel of an audio signal of the required frequency components decreases the current flow through the electric discharge device 226 so that the de-energization of the relay winding permits the movable contact 257 to move from engagement with the contact 255 and into engagement with contact 256 stopping flow of direct current through the control winding 300. The impedances of the windings 199a and 216a vary directly as the current flow in the control winding 301 and phase-shift the voltages or firing pulse supplied to the control elements of the silicon controlled rectifiers relative to the supply voltage, thereby allowing the flow of current through the rectifiers to the solenoid valve V. The

switching circuit is adapted to render the rectifiers conductive whenever an audio input signal of predetermined magnitude is received by the channel and the current flow through the rectifiers whenever they are conductive is sufficient to open the solenoid valve to its position allowing maximum liquid flow. When no audio input signal is received by the channel, the current in the control winding of the magnetic amplifier 301 prevents the switching circuit 165a from supplying current to the particular valve controlled by the channel, the valve being in normally closed position or in a position allowing a minimum liquid flow therewith.

It will thus be seen that whereas the energization of the illuminating system as controlled by the switching circuit 165 varies in accordance with the magnitude of current in the magnetic amplifier control winding 166a, the valve is energized to either a fully open position or a position allowing minimum liquid flow.

It will also be seen that the amplitudes of the sprays in the spray systems is determined by the occurrence of particular frequency components in the audio input signal. When the signal includes frequencies which are acceptable by any particular channel, the solenoid valve associated with the channel is opened to increase the liquid flow from the spray nozzles and the amplitudes of the sprays controllable by the valve. In addition, the intensities of the lights in the particular illuminating system associated with the channel are varied in accordance with the amplitudes of the frequency components in the channel.

It will also be seen that the sensitivity of the switching means in any channel for supplying current to a solenoid valve and illuminating system is controllable by the potentiometer 76. Additional sensitivity controls for the illumination and spray systems are provided by the potentiometers 140 and 228, respectively.

The additional channels for filtering the audio input signal and transmitting other preselected bands of frequency components, similarly control the other illuminating systems and solenoid valves. All of the channels are connected in parallel whereby the audio input signal which is applied across the grid and cathode of the amplifier electric discharge device 89 in channel I is also applied across the grid and cathode of the corresponding amplifiers in the additional channels. The grid of each of these amplifiers is connected to the slide contact 78 of the potentiometer 76 by the conductor C and their cathodes connected to ground through their bias resistors so that all the channels are adapted to receive the input signal. The frequency selectivity of each of the channels, of course, is determined by the characteristics of the filter included therein, although the channel which controls the solenoid 55 should be designed to transmit all of the audio frequencies. For purposes of illustration, a different type of filter 99a is shown in channel II than is employed in channel I, however, any suitable filter may be used.

The foregoing description of the invention is explanatory only, and changes in the details of the construction illustrated may be made by those skilled in the art, within the scope of the appended claims, without departing from the spirit of the invention.

What is claimed and desired to be secured by Letters Patent is:

1. A device for controlling a plurality of water spray fountains and a plurality of illuminating systems therefor, comprising: first means for providing an input potential having audio frequency components of varying amplitudes; a plurality of filtering means for filtering said potential connected to said first means, each said filtering means comprising a frequency band-pass circuit adapted to transmit a particular frequency range of said components; illumination control means operatively associated with each said filtering means, each of said control means responsive to the potential components transmitted by

a particular one of said filtering means for varying the intensity of illumination of a particular one of said illuminating systems in accordance with the varying amplitude of the potential components transmitted by said particular filtering means; fountain control means operatively associated with each said filtering means for increasing the water flow of a particular one of said fountains when the amplitude of the components transmitted by the filtering means exceeds a predetermined value and means responsive to said input potential for increasing the water flow of all said spray fountains upon the occurrence in said potential of an audio frequency component of a predetermined amplitude.

2. A device for controlling a plurality of water spray fountains and a plurality of illuminating systems therefor, comprising: first means for providing an input potential having audio frequency components of varying amplitudes; a plurality of filtering means for filtering said potential connected to said first means, each said filtering means comprising a frequency band-pass circuit adapted to transmit a particular frequency range of said components; illumination control means operatively associated with each said filtering means, each of said control means responsive to the components transmitted by a particular one of said filtering means for varying the intensity of illumination of a particular one of said illuminating systems in accordance with a varying amplitude characteristic of the components transmitted by said particular filtering means; a plurality of spray control means, each operatively associated with a particular one of said filtering means for varying the water flow of a particular one of said fountains upon the occurrence in said potential of a component of a predetermined amplitude and frequency adapted to be transmitted by its particular associated filtering means; and spray control means operatively associated with all said spray fountains and said first means for varying the water flow of all said fountains upon the occurrence in said potential of any audio frequency component of a predetermined amplitude.

3. A fountain spray system including: a plurality of individual spray nozzles for ejecting sprays of liquid; means connected to said nozzles for supplying liquid under pressure to said nozzles; means for individually controlling the flow of liquid to each said spray nozzle from said supply means, said controlling means comprising a separate valve means associated with each of said spray nozzles for controlling the flow of liquid from said supply means to each of said nozzles; and means responsive to voltage signals of predetermined audio frequencies for operating the valve means when the amplitude of said voltage signals exceeds a predetermined value.

4. A fountain spray system including: a plurality of individual spray nozzles for ejecting sprays of liquid; means connected to said nozzles for supplying liquid under pressure to said nozzles; means for individually controlling the flow of liquid to each said spray nozzle from said supply means, said controlling means comprising a separate valve means associated with each of said spray nozzles for controlling the flow of liquid from said supply means to each of said nozzles; and a plurality of valve control means, each responsive to a particular audio frequency electrical signal for operating a particular valve means whenever the amplitude of the signal exceeds a predetermined value.

5. A fountain installation comprising: a plurality of individual spray nozzles for ejecting sprays of liquid, means connected to said nozzles comprising a pump for supplying liquid under pressure to said nozzles; separate valve means associated with each of said spray nozzles for controlling the flow of liquid pumped from said pump to each of the nozzles; illuminating means mounted adjacent said spray nozzles for illuminating the sprays; means connected to said illuminating means for varying the intensity of illumination from said illuminating means

in accordance with the amplitude of an audio frequency sound; and means connected to said valve means for opening said valve means to increase the amplitude of the sprays whenever the amplitude of said audio frequency sound exceeds a predetermined value.

6. A fountain installation comprising: a plurality of individual spray nozzles for ejecting sprays of liquid; means connected to said nozzles comprising a pump for supplying liquid under pressure to said nozzles; separate valve means associated with each of said spray nozzles for controlling the flow of liquid pumped from said pump to each of the nozzles; separate control means for each of said valve means, said control means each being responsive to a different audio frequency voltage signal for controlling the operation of the valve means; a plurality of illuminating means for illuminating the sprays; and separate illuminating control means operatively associated with each said illuminating means, each said illuminating control means being responsive to a voltage signal of a different audio frequency for controlling the illuminating intensity of its associated illuminating means in accordance with the amplitude of the voltage signal.

7. A fountain spray system including: a plurality of individual spray nozzles for ejecting sprays of liquid; means connected to said nozzles for supplying liquid under pressure to said nozzles, said supply means comprising a pump; a valve means associated with said spray nozzles for controlling the flow of liquid pumped by said pump to each of the nozzles; means for providing electric current having audio frequency components; means connected to said last mentioned means for rectifying said current for deriving uni-directional control currents therefrom; and means responsive to said uni-directional currents for operating said valve means to increase the flow of liquid to each of said nozzles whenever the amplitude of any of said audio frequency current components exceeds a predetermined value.

8. A fountain spray system including: a plurality of individual spray nozzles for ejecting sprays of liquid; means connected to said nozzles for supplying liquid under pressure to said nozzles, said supply means comprising a pump; a valve means associated with said spray nozzles for controlling the flow of liquid pumped by said pump to each of the nozzles; illuminating means for said sprays; means for providing electric current having audio frequency components; means for rectifying said current for deriving uni-directional control currents therefrom; means responsive to said uni-directional currents for controlling the energization of said illuminating means in accordance with the magnitude of said audio frequency components; and means responsive to said uni-directional currents for operating said valve means to increase the flow of liquid to each of said nozzles whenever the amplitude of any of

said audio frequency components exceeds a predetermined value.

9. A fountain spray system including: a plurality of individual spray nozzles for ejecting sprays of liquid; means connected to said nozzles for supplying liquid under pressure to said nozzles, said supply means comprising a pump; separate valve means associated with each of said spray nozzles for controlling the flow of liquid pumped by said pump to each of the nozzles; means for providing a potential having audio frequency components of varying amplitudes; a plurality of filter means for said potential connected to said last mentioned means, each said filter means adapted to transmit a control potential consisting of a different band of said components; and separate control means associated with each valve means, each control means being responsive to the control potential from a different one of said filter means for opening its associated valve means whenever the control potential is of a predetermined magnitude.

10. A fountain spray system including: a plurality of individual spray nozzles for ejecting sprays of liquid; means connected to said spray nozzles for supplying liquid under pressure to said nozzles, said supply means comprising a pump; separate valve means associated with each of said spray nozzles for controlling the flow of liquid pumped by said pump to each of the nozzles; means for providing a potential having audio frequency components of varying amplitudes; a plurality of filter means for said potential connected to said last mentioned means, each said filter means adapted to transmit a control potential consisting of a different band of said components; separate control means associated with each valve means, each control means being responsive to the control potential from a different one of said filter means for opening its associated valve means whenever the control potential is of a predetermined magnitude; a plurality of illuminating means for illuminating the sprays; and separate control means associated with each illuminating means, each said illuminating control means being responsive to vary the energization of its associated illuminating means in accordance with the varying amplitude of the control potential from a particular one of said filter means.
